UNITED STATES PATENT OFFICE.

OTTO GRAVENHORST AND LUIS HÖLLRIGL, OF BUENOS AIRES, ARGENTINA.

REFILLABLE MULTIPLE FUSE.

1,405,778.

Specification of Letters Patent.

Patented Feb. 7, 1922.

Application filed December 29, 1919. Serial No. 348,216.

To all whom it may concern:

Be it known that we OTTO GRAVENHORST, Argentina, and Luis Höllrigl, a Swiss subject, both residing at Buenos Aires, Argentina, Galería Guemes 440/1, have invented a certain new and useful Improvement in a Refillable Multiple Fuse, of which the following is a specification.

Our invention relates to circuit makers, 10 and more particularly to a magazine fuse adapted semi-automatically to re-establish an electrical circuit by the substitution of another fuse when the circuit has been broken by the rupture of the protective 15 fusible element.

Our invention has for its object the provision of a self-contained device adapted to afford means for semi-automatic replacement of a burnt out fuse whereby the circuit may 20 be expeditiously re-established without the use of tools or skilled labor or knowledge. A further object is the provision of a manually operable device of the magazine type, permitting repeated use and capable of 25 manipulation with the same ease and simplicity as a spring or snap-switch. A particular object is the provision of a device of the described class which shall have the capacity to permit not only repeated resetting of the 30 connection through a fuse-link or fuse wire without dismemberment or skilled attention, but which device shall also be capable of refilling for reuse. Other objects attained by our invention will appear from the ensuing detailed description thereof.

Our invention consists in a device having a fixed base adapted to receive the circuit terminals, a revoluble housing associated therewith comprising a magazine and containing 40 a series of mutually insulated fusible elements separately mounted therein, and means whereby these fusible elements may be successively brought into intimate electrical contact with the circuit terminals and 45 such intimacy of contact operatively maintained, which device we have termed a refillable multiple fuse.

Reference is made to the drawings forming part of this specification for a more detailed 50 disclosure of the preferred form in which our invention may be physically embodied, in which drawings like numerals of reference indicate like parts throughout the several views, and in which Figure 1 is a vertical 55 sectional view of the assembled circuit maker; Figure 2 is a view in perspective;

Figure 3 is a plan view of the bottom of the revoluble housing lettered A in Figure 1; Figure 4 is a plan view of the top of the fixed base lettered B in Figure 1; Figure 5 shows an enlarged detail of a part of the housing and base, in vertical section, upon the line V—V of Figure 3; and Figure 6 shows an enlarged detail in vertical section upon the line VI—VI of Fig. 5.

The circuit maker essentially comprises two relatively movable parts, the top A which constitutes a housing for the fusible elements and which is preferably of a vitreous material, as porcelain, and is in circular form, and a supporting base B of like material adapted to be permanently fixed in association with the wires of the circuit to be closed through said fusible elements. The part A has a series of channels 1, 1 there-through, regularly disposed at spaced intervals thereabout, these channels having openings 2, 2 adjacent the top of the housing to afford vents for the gases of fusion and also to permit inspection and to constitute 80 eyes through which the fuse wires 3, 3 may be conveniently threaded, permitting their attachment at their ends to the binding screws 4 and 5, respectively. The screw 4 binds one end of the fuse to the terminal plate 6, and the screw 5 binds the other end of the fuse to the terminal plate 7, which plates are secured by screws, as shown, to the body of the housing. The plates 6 and 7 are separated by the circular boss 8 formed 90 by extension of the body of the housing, which boss enters a corresponding recess 9 in the base B. Upon this base are the contact plates 10 and 11 associated respectively with the binding posts 12 and 13, which receive 95 respectively the line circuit terminals between pairs of clamping nuts 14 and 15. To assure a positive seating of the fuse contacts with the line contacts, and assure accuracy in this regard, the plates 6 and 7 have 100 the extension or shoulders 16 formed thereon, and the plates 10 and 11 have corresponding recesses or grooves 17 formed therein which function as hereinafter described upon rotation of the housing A upon the spindle 105 20 which passes vertically therethrough and through the base B in the channel 18, 18, securing the parts together by the screw-threaded extension 19 which engages a nut thereon. The upper end of the spindle 20 has the adjustable screw cap 21 which 110 tensions a leaf spring 22 against the housing A,

permitting relative vertical movement of the housing A with relation to the base B when the former is rotated to advance a fusible element to circuit-closing position. By virtue of the vertical play afforded, the shoulders 16 upon the plates 6 and 7, when they strike the rounded edge of the plates 10 and 11, ride upward and across the upper faces of these plates until the groove 17 is encountered, when they seat positively therein under spring stress. A pointer 23 or like visible indicator, upon the base, shows the registry of contact by its correspondence with one of the marks 24 carried by the revolute housing A.

It will be obvious that the fusible elements carried by the device may be numerous. Twelve are shown as a convenient illustration. When all have been dissipated or broken or otherwise become unserviceable, the device may be reloaded. If desired, the vents 2, 2 may be sealed, ample space being afforded for dissipation of any products of combustion by the clearance between the two bodies A and B.

By our device, a compact, simple and safe means is afforded, and one particularly adapted to domestic installation, though its utility is not circumscribed, since it is adapted to all classes of usage, and may be suitably designed for larger amperage.

Having thus described our invention and without desiring to be understood as limiting its utilities, advantages or scope, save as specified in the appended claims, we claim:

1. In an electro-protective device, in combination, a base, line terminals thereon, contact plates secured to said terminals, a channelled, rotatable cover, a plurality of fuses separately mounted in the channels thereof, a pair of terminal plates for each fuse, a circular lug depending from said cover adapted to engage a corresponding groove in said base and adapted to preserve the relative positions of the members when the cover is rotated, the line contact plates being radially disposed relatively to an axial spin-

dle upon which the cover is rotated, the fuse contact plates being similarly disposed; means adapted to insure registry between the successive pairs of fuse plates and the line plates, said means consisting of an interrupted tongue upon said fuse plates, and a corresponding interrupted groove on said line plates, and a spring upon said spindle adapted to exert its force against said cover.

2. In an electro-protective device of the refillable multiple fuse type, in combination, a circular chambered base having an annular groove in the bottom of its chamber, a channelled fuse-holding magazine-cover having a cylindrical body portion adapted to extend into the chamber of the base; an annular lug upon said body portion of the cover adapted to register with said annular groove; an axial spindle extending through the base and cover about which the cover may be rotated; a pair of radially disposed contact plates upon said base, separated by the annular groove therein and extending above the bottom of its chamber; a plurality of fuses disposed in the channels of said magazine-cover; pairs of radially disposed terminal plates associated with each fuse mounted on the body-portion of said cover, each pair being mutually separated by the annular lug upon said body portion, and having a downwardly projecting tongue adapted successively to engage the contact plates upon the base upon rotation of the cover, such engagement causing a vertical movement of the cover relatively to the base as the tongues upon the fuse terminal plates ride over the contact plates upon the base, and means comprising a spring upon said spindle adapted to hold the plates in intimate contact.

In testimony whereof we affix our signatures in presence of two witnesses.

OTTO GRAVENHORST.
LUIS HÖLLRIGL.
